US0D1108269S

(12) **United States Design Patent** (10) Patent No.: **US D1,108,269 S**
(45) Date of Patent: ** Jan. 6, 2026

(54) **EYEDROP BOTTLE**

(71) Applicant: **OCUSUN OPHTHALMIC PHARMACEUTICAL (GUANGZHOU) CO., LTD.**, Guangzhou (CN)

(72) Inventors: **Meirong Wu**, Guangdong (CN); **Junfeng Yu**, Guangdong (CN); **Peisheng Zhang**, Guangdong (CN)

(73) Assignee: **Ocusun Ophthalmic Pharmaceutical (Guangzhou) Co., Ltd.**, Guangdong (CN)

(**) Term: **15 Years**

(21) Appl. No.: **35/520,830**

(22) Filed: **May 6, 2023**

(80) **Hague Agreement Data**

Int. Filing Date: **May 6, 2023**

Int. Reg. No.: **DM/230287**

Int. Reg. Date: **May 6, 2023**

Int. Reg. Pub. Date: **May 10, 2024**

(30) **Foreign Application Priority Data**

Nov. 8, 2022 (CN) 202230743516.0

(51) LOC (15) Cl. **07-01**

(52) U.S. Cl.

USPC **D9/556**; D9/529; D9/559
